AGITATING APPARATUS FOR THE SUPPLY
HOPPERS OF PLASTIC-CONCRETE PUMPSCharles F. Ball, Wauwatosa, Wis., assignor to
Chain Belt Company, Milwaukee, Wis., a cor-
poration of Wisconsin

Application January 17, 1938, Serial No. 185,422

4 Claims. (Cl. 259—169)

The invention relates to agitating apparatus for the supply hoppers of plastic-concrete pumps, typical examples of which may be found in the prior U. S. Patent No. 2,017,975 granted October 5 22, 1935, to J. C. Kooyman, and in my prior Patent No. 2,062,200, granted November 24, 1936.

In feeding such pumps, the plastic mixture is usually intermittently deposited from a concrete mixer of either the stationary or transit type into 10 a conical hopper having sufficient capacity to insure a continuous feed to the pump during intervals between such deposits. The hoppers ordinarily surmount the inlet valve of the pump and feed directly thereto by gravity.

15 It is well known that plastic concrete mixtures, particularly the wetter mixes, unless kept in motion have a marked tendency to segregate, i. e. for the heavier aggregates to work their way to the bottom, with the lighter aggregates and the 20 binder "floating" above them. There is also a tendency toward mechanical binding or interlocking of the pieces of aggregate—as distinguished from setting resulting from chemical reactions in the binder—which retards or prevents 25 flow of the mixture.

It frequently becomes necessary in large concrete placement operations to temporarily stop pumping while mixture remains in the hopper, as for example, to relocate the discharge end of 30 the line, and it has therefore been found highly desirable to provide means for agitating the mixture in the hopper to prevent segregation and/or mechanical interlocking or binding of the aggregates during such period. It has also been found 35 that when the pump is running portions of the mixture in the conical hopper have a tendency to feed faster than other portions, thereby causing "channeling," with the result that the less active portions tend to become stagnant and harden.

40 The present invention has for one of its primary objects the provision of agitating or re-mixing apparatus for these conical hoppers which will effectively maintain the mixture in good working condition by preventing segregation, 45 "channeling," and mechanical interlock of the aggregates, whether the pump be running or stopped.

It is also an object of the invention to provide 50 apparatus of this character functioning adjacent the upper portions of the conical walls of the hopper to work the mixture in this location away from said walls and toward the center, thereby preventing stagnation and hardening of the mixture in this zone.

55 A still further object is to provide agitating

apparatus of the type described which will not appreciably interfere with the deposit of the mixture into the hopper from the mixer.

A still further object of the invention is to provide means for preventing the agitator elements from merely moving the mass of mixture bodily in the hopper without producing any material agitation or re-mixing thereof.

With the above and other objects in view, which will appear as the description proceeds, the 10 invention consists in the novel details of construction, and combinations and arrangements of parts, more fully hereinafter described and particularly pointed out in the appended claims.

Referring to the accompanying drawings forming 15 a part of this specification, in which like reference characters designate like parts in all the views—

Figure 1 is a side elevational view of a concrete 20 pump of the general type disclosed and claimed in the above mentioned Kooyman and Ball patents, having one form of agitating apparatus constructed in accordance with the present invention applied to the supply hopper thereof;

Fig. 2 is a fragmentary elevational view on a 25 enlarged scale of the hopper and the agitating apparatus illustrated in Figure 1, as seen from the left of said figure, a portion of the parts being broken away and shown in section;

Fig. 3 is a central vertical sectional view taken 30 approximately on the plane indicated by the line 3—3 of Fig. 2 looking in the direction of the arrows;

Fig. 4, is a plan view partly broken away of the 35 parts shown in Fig. 3, and

Fig. 5 is a fragmentary sectional elevational view of a slightly modified form of the invention.

Referring more particularly to Fig. 1, the pump comprises a chassis 10 upon which is mounted a working cylinder 11 in which reciprocates a piston 40 12 which is moved back and forth by crank mechanism, not shown, but actuated by a crank shaft 13 which is driven by spur gearing 14 from a countershaft 15. The countershaft in turn is driven by means of a V-belt drive 16 driving the pulley 17 45 carried by the countershaft 15 and deriving power from a pulley 18 which is loosely mounted upon a jack shaft 19, see Fig. 2, which shaft is journaled in an extension 20 of a housing 21. This housing contains a main clutch and suitable gearing for 50 transmitting power to the shaft 19 from the power shaft 22 of an internal combustion engine or other prime mover contained within a housing 23 mounted upon the pump frame.

The working cylinder 11 has associated with it 55

- an inlet valve 25 and an outlet valve 26 the latter of which discharges to the pipe line 27 through which the plastic concrete is conducted from the pump to the point of placement. The inlet valve 25 is surmounted by the supply hopper 30 which feeds directly to the inlet passage of valve 25 by gravity and which may have mounted in its lower portion an agitating mechanism 31 of the type described and claimed in my prior co-pending application, Ser. No. 740,328, filed August 17, 1934, now Patent No. 2,116,473, granted May 3, 1938 which agitating mechanism may be driven by a chain drive 32, see Fig. 1, from the crank shaft 13.
- The agitating mechanism constituting the present invention comprises an annulus 35, here shown as being constructed of angle iron, which surrounds the upper edge of the hopper 30 and has rigidly secured to it one or more agitating blades or paddles 36 extending downwardly into the upper portion of the hopper parallel to and closely adjacent the conical walls thereof, as will be readily understood from Figs. 3 and 4. These agitating members have inclined portions 37 which closely approach the inner surface of the hopper walls and as the members are rotated in a clockwise direction, as viewed in Fig. 4, they serve to work the plastic concrete resting upon this portion of the walls away therefrom and toward the center, thereby preventing stagnation of the mixture in this zone and consequent hardening of it upon the said walls. The agitation thus provided also prevents segregation of the heavier and lighter constituents and tends to keep the mixture in good working condition.
- The annulus 35 is provided with a plurality of depending brackets 40 arranged at spaced intervals and secured to an annular gear 41 which is mounted for concentric rotation relative to the hopper axis upon a plurality of circumferentially spaced supporting rollers 42 which are journaled in brackets 43 welded or otherwise rigidly secured to a supporting ring of angle iron 44, which in turn is welded or otherwise rigidly secured to the exterior of the hopper a short distance below its upper edge, as is clearly shown in Figures 1, 2 and 3.
- For driving the annular gear 41 a pinion 45 is provided meshing therewith, which pinion is carried by a vertical shaft 46 journaled in a gear housing 47 which is supported by a suitable bracket 47' welded or otherwise rigidly secured to the exterior of the hopper. Obviously, a chain and sprocket drive may be substituted for the spur gear 41 and pinion 45, if desired. The housing 47 contains suitable bevel, worm, helical or other gearing for transmitting power to the shaft 46 from the horizontal shaft 48, which shaft is provided with a sprocket 49 about which passes a chain 50 which also engages a sprocket 51 rigidly secured to the jack shaft 19, see Fig. 2. The agitating mechanism is thus constantly driven from the jack shaft 19 whenever the master clutch in housing 21 is engaged; and suitable manual clutch mechanism is associated with the sprocket 51 for engagement with and disengagement from the V-belt pulley 18 whereby provision is made for stopping the drive to the pump piston 12 while permitting continued operation of the agitator. As best shown in Fig. 2, this clutch mechanism comprises a manually operable member 55 slidably mounted upon the jack shaft 18 and provided with a detent ball or plunger 56 adapted to be received in one or the other of the circumferential grooves 57 provided adjacent the outer end of shaft 19. The clutch

member 55 also carries a plurality of pins 58 slidably mounted in apertures 59 extending through the hub of sprocket 51 with the inner ends of the said pins 58 being receivable in and removable from recesses 60 formed in the hub of the V-belt pulley 18. It thus results that when the parts are in the positions illustrated in Fig. 2, power will be transmitted from shaft 19 through sprocket 51 and pins 58 to pulley 18 and the crank shaft 13 of the pump thereby actuated, whereas if the member 55 be manually moved toward the right, as viewed in Fig. 2, until its detent 56 engages the right hand groove 57 the inner ends of the pins 58 will be withdrawn from the recesses 60 in pulley 18 and the drive to the pump crank shaft 13 will be thus broken. Engagement and disengagement of clutch pins 58 is preferably effected with the parts at rest, through initial disengagement of the main clutch in housing 21, as obviously this will facilitate entry or withdrawal of pins 58 into and from recesses 60.

As will be apparent from what has been above described, when the jack shaft 19 is rotated by the prime mover within the housing 23 its movement will be transmitted through the chain and sprocket mechanism 49, 50 and 51, shaft 48, the gearing within housing 47 and shaft 46 to the pinion 45 and thence to the annular gear 41, which in turn will transmit the motion through the brackets 40 to the angle iron annulus 35 and the agitating members 36 thereby continuously agitating the mixture within the upper portion of the hopper 30 and especially that portion immediately adjacent its upper inclined walls. If the clutch mechanism 55 be in engagement as shown in Fig. 2, the pump piston 12 will be reciprocated from the crank shaft 13 and the mixture which is within the hopper 30 will be drawn into the cylinder 11 through the inlet valve 25 and then expelled through the outlet valve 26 to the pipe line 27. On the other hand, if the clutch mechanism 55 be disengaged the pump drive will be stopped though the agitator drive will continue.

Instead of having the agitating members 36 rigidly constructed as illustrated in Figs. 1 to 4, inclusive, the said members may be pivotally mounted as indicated at 60 in Fig. 5 to suitable brackets 61 carried by the annulus 35. This will permit the agitators to swing away from the hopper 30 should a piece of aggregate be caught beneath them.

To prevent the entire mass of mixture in the hopper being bodily moved around by the blades 36 without agitation, I preferably provide a fixed plate or baffle 65, which may have rigidly secured to it a rod or pipe 66, which is adjustably clamped in the split end 67 of a horizontally extending arm 68. The other end of said arm is adjustably secured to the upper end of a rod or stand 69, carried by a bracket 70, welded or otherwise secured to the hopper 30. The arm 68 may be secured on standard 69 in various arcuate positions to properly dispose the baffle 65 in the hopper, and the said baffle may in turn be arcuately and vertically adjusted relative to arm 68 through the clamping connection between the split end 67 of the arm and the rod 66, as will be readily understood. The said baffle may thus be adjusted to a variety of positions, as occasion may require, and since it does not move after being adjusted, it acts as a fixed plow which prevents rotation of the mixture mass as a body and insures the desired agitation.

While one form of the invention has been illus-

trated and described it is obvious that those skilled in the art may vary the details of construction as well as the precise arrangement of parts without departing from the spirit of the invention and therefore it is not wished to be limited to the above disclosure except as may be required by the claims.

5 What is claimed is:

1. In concrete agitating mechanism for the supply hopper of a plastic-concrete pump, the combination with a non-rotatable hopper having a bottom opening affording continuous free communication with the inlet passage of the pump, of an annular structure mounted for concentric rotation about the exterior thereof; agitating members carried by said annular structure and extending into the hopper in position to act upon concrete mixture therein; power actuated means arranged to drive said annular structure; and a fixed baffle extending downwardly in said hopper in spaced relation to its peripheral wall and axis arranged to prevent said agitating members from rotating the concrete mass bodily without agitation.
2. In concrete agitating mechanism for the supply hopper of a plastic-concrete pump, the combination with a non-rotatable hopper having a bottom opening affording continuous free communication with the inlet passage of the pump of agitating members mounted for rotation within the hopper and arranged to extend into the concrete mass therein; power actuated means for rotating said members; a support exterior of the hopper; an arm adjustably secured to said support and extending over the hopper; and a baffle adjustably secured to said arm and depending into the hopper in spaced relation to its periph-

eral wall and axis arranged to enter the mass and prevent its rotation bodily by said agitating members.

3. In apparatus for agitating pre-mixed concrete in the supply hopper of a concrete pump to prevent segregation of the constituents of the mixture, the combination with a stationary pump hopper having a bottom opening affording continuous free communication with the inlet passage of the pump, of a structure mounted upon said hopper for rotation about the exterior thereof; agitating means carried by and rotatable with said structure, consisting of a member extending from said structure downwardly in said hopper adjacent the side wall thereof and terminating short of said opening whereby the latter is maintained free and unobstructed; and power actuated means arranged to drive said structure.

4. In apparatus for agitating pre-mixed concrete in the supply hopper of a concrete pump to prevent segregation of the constituents of the mixture, the combination with a stationary coniform pump hopper having a bottom opening affording continuous free communication with the inlet passage of the pump, of a structure mounted upon said hopper for rotation about the exterior thereof; agitating means carried by and rotatable with said structure, consisting of elongated arms extending from said structure downwardly in said hopper adjacent the side wall thereof and arranged to work the mixture away from said wall toward the center of said hopper, said arms terminating short of said opening whereby the latter is maintained free and unobstructed; and power actuated means arranged to drive said structure.

CHARLES F. BALL.
